UNITED STATES PATENT OFFICE.

SAMUEL FINLEY BREESE MORSE AND SAMUEL RITCHIE TUGGLE, OF
HOUSTON, TEXAS.

CINDER-GUARD.

SPECIFICATION forming part of Letters Patent No. 690,309, dated December 31, 1901.

Application filed August 20, 1900. Serial No. 27,463. (No model.)

To all whom it may concern:

Be it known that we, SAMUEL FINLEY BREESE MORSE and SAMUEL RITCHIE TUGGLE, citizens of the United States, residing at Houston, in the county of Harris and State of Texas, have invented a new and useful Cinder-Guard, of which the following is a specification.

This invention relates to cinder-guards, and the present improvement contemplates a device of this character adapted for application to the panels between car-windows and capable of being easily reversed to change the position thereof in accordance with the movement of a car in opposite directions, the entire device being readily attachable and detachable to and from a car-panel and having structural deflecting features which materially augment the efficiency of the guard in preventing cinders and other products of combustion from entering a car-window and permit the unrestricted ventilation of a car without the liability of soiling the apparel of passengers and the inconvenience of flying cinders.

The invention consists in the construction, arrangement, and general organization of the several instrumentalities contributing to the general effectiveness of the guard, which will be more fully hereinafter described and claimed and subject to substitution of well-known equivalents and changes in the form, size, proportions, and minor details within the purview of the invention.

In the drawings, Figure 1 is a perspective view of a portion of a passenger coach or car, showing the improved guard applied thereto in operative position. Fig. 2 is a front elevation of the improved guard. Fig. 3 is a transverse vertical section of the same. Fig. 4 is a horizontal section showing the guard proper adjusted in operative angular position. Fig. 5 is a bottom plan view of the improved device. Figs. 6 and 7 are detail views of hanging devices for the improved guard which are respectively secured to the panel and the guard.

Similar numerals of reference are employed to indicate corresponding parts in the several views.

The numeral 1 designates the support or

frame constructed of sheet metal or other suitable material and having a central concave recess 2, extending vertically full length thereof, and opposite side ledges 3, projecting outwardly and inclined toward each other to form deflecting-faces, which also extend the full vertical length of the device. Secured to the top and bottom of the support or frame are cap and foot plates 4 and 5 of triangular shape, having their apices or reduced portions extending equally outward beyond the front of the support or frame and the plane of their outer edges 6 coinciding with the planes of the ledges 3. The back or inner edges 7 of the cap and foot plates are formed with opposite curved recesses 8 to fit over the usual moldings at opposite sides of a car-panel at the outer side edge portions of the window-frames or structures, the faces of the panels standing within the plane of the outer extent of the said moldings or beadings on each side and at the bottom and top of said panels to thereby form recesses, and the intermediate portions of the edges 7 enter the latter recesses thus formed to provide a snug inclosure between the two plates 4 and 5, to prevent entrance of cinders or products of combustion within the inclosure and injury to the surface of the panel and also to afford convenient and effective means for hanging the improved device in a convenient manner to facilitate attachment and removal thereof and also produce a stable application to resist any tendency to accidental disengagement of the same. To provide inclosures at the inner portions of the ledges 3, the inner portions of the latter are extended inwardly in straight planes, as at 9, to embrace the said moldings or beadings at opposite sides of the panel. The foot-plate 5 is also provided with supplemental deflectors 10 at the inner portions of the opposite edges 6, which depend over the panel-sill, continuing from the window-sills and constructed by a longitudinal ledge 11 extending the full length of the car side and having its upper surface inclined downwardly. The said supplemental deflectors are recessed in such a manner as to accommodate and provide a close fitting against the said inclined surface of the ledge and also thereby bring the bottom of the

entire device in close engaging relation with the ledge. The said supplemental deflectors have the same angular deflecting plane as the ledges 3 and operate to throw out the currents of cinder-laden air following closely along the lower side portion of a car under the said ledge and having a rising tendency adjacent open windows. The cap and foot plates 4 and 5 are also reinforced against 10 bending or breakage by braces 12, secured thereto and the back wall of the recess 2, and in the outer reduced or angular extremities 13 of the said plates the opposite ends of a vertical pintle-bar 14 are pivotally mounted, 15 the lower end of said bar projecting below the foot-plate and having one end of an S-shaped spring-catch 15 secured thereon to turn therewith, the inner reduced portion of the said catch being disposed in the plane of 20 opposite diagonally-arranged notched keepers 16, having inner downwardly-inclined riding edges 17 and outer depending stop projections 18 to guide the catch to the notches of the opposite keepers and to prevent the 25 same from being outturned, and thereby insure a specific turning operation of the pintle-bar 14 for a purpose which will hereinafter appear.

A guard 19 is firmly attached to the pintle-bar 14, the latter having a flat or square surface bearing against the guard. The guard is dished and has opposite curved sides 20, and when formed of sheet metal the said guard will be rigidly reinforced against bending by the force of the air-currents by a marginal wire binding 21 and also by cross-braces 22. The pintle-bar extends centrally over the dished face of the guard, and the braces 22 are also applied to the same face, so that 30 the opposite deflecting side or face of the guard will be perfectly smooth and unbroken at any point by angular projections or other devices that would have a tendency to retard the movement of the cinders or products of 35 combustion thereover.

Sockets 23 are secured in the center of the panel or panels to which the guard is attached and disposed in vertical alinement at suitable elevations to removably receive hanger-heads 40 24, attached to the center of the rear portion of the support or frame and also in corresponding vertical alinement relatively to the sockets. The hanger-heads can be easily inserted in or removed from the sockets by a 45 vertical movement of the entire device in reverse directions, and by the use of this particular type of suspending devices the guard as an entirety will be prevented from having lateral movement, as well as displacing vertical movement, from accidental causes.

In the use of the improved device the dished side or face of the guard will be arranged toward the rear relatively to the direction of movement of the car and so that the opposite 55 smooth face will be in position to receive the impact of the currents of air laden with cinders and products of combustion, and the

said guard will then have an oblique angular direction or position relatively to the side of the car in a plane at a right-angle to the then forward ledge, and by this complete arrangement the cinder-laden currents of air will be caused to first ride outwardly over the said ledge and strike the deflecting face of the guard and slide off over the outer curved side 70 edge of the latter away from the car side and clear of the open windows in rear of the guard. As many of the guards may be applied to a car side as desired and found necessary, and it will be observed that the improved device 75 can be reversed for use on the same side of a car to similarly operate when the latter is moving in different directions, or it may be applied to either side of a car. The seat or recess 2 permits the guard to be readily turned 80 for reversing purposes, provides for a close arrangement to the car side, and allows the inner side edge of the guard to be located within the plane of the outermost projection of the ledge on either side to avoid escape or 85 passage between the deflecting-face of the guard and the wall of the recess of any of the air-currents carrying the cinders or products of combustion. The smooth wall of the recess also prevents the congregation of cinders 90 or products of combustion thereon, and the spring-catch 15 when in engagement with either one of the keepers 16 will positively maintain the guard against movement when 95 adjusted in either of its positions. To render the device more compact for storage, the spring-catch is released, and the guard can then be arranged across the plates 4 and 5.

The improved device is simple in its construction and possesses all the necessary durable qualifications, and in the manufacture of the same all metal or a selected composition of wood and metal will be used. If metal be used, it will be treated so as to make it non-corrosive and will also be of a light nature.

Having thus described the invention, what is claimed as new is—

1. In a device of the class set forth, the combination of a support having an outer concave recess with opposite side marginal ledges 115 which are straight and each converged toward the other in an outward direction, upper and lower horizontally-disposed plates of triangular shape projecting outwardly beyond the planes of the ledges and the recess, a vertically-disposed guard pivotally held by the said supporting-plates and reversible to bring the opposite side edges in alinement with the respective marginal ledges at the opposite sides of the recess and with the side edges of 120 the said plates, the said side edges of the guard being always outside of the confines of the recess, whereby the guard may be adjusted to either one of two angular positions in planes parallel with the opposite side edges of the 125 plates, and means for positively locking the guard in either of its adjusted positions to prevent movement thereof by the air-currents striking the same, the said means being lo- 130

cated against the under side of the bottom plate so as to have the upper portion of the said plate clear for the operation of the guard.

2. In a device of the character set forth, the combination of a support having an outer concave recess with opposite side marginal ledges inclined toward each other, angular cap and foot plates standing outwardly from the support, the foot-plate having a pair of diagonally-disposed keepers on the under side of the same, a pintle-bar pivotally mounted in the said plates, the lower extremity of the bar depending below the foot-plate, a spring catch secured to and movable with the said depending portion of the bar for engagement with the keepers, and a vertically-disposed guard secured to the said bar and having opposite deflecting side edges.

3. In a device of the character set forth, the

combination of a support for application to a car-panel and provided with inward extensions at the opposite sides to embrace the beading or molding at opposite sides of the said panel continuous with side ledges inclined outwardly toward each other and forming margins for an outer concave recess, and a vertically-disposed pivotally-mounted reversible guard located in front of said recess and having opposite deflecting side edges movable within the plane of the recess.

In testimony that we claim the foregoing as our own we have hereto affixed our signatures in the presence of two witnesses.
